(57) **CLAIM**

The ornamental design for an automobile tire as shown and described.

DESCRIPTION

FIG. 1 is a perspective view of an automobile tire showing our design;

FIG. 2 is a right side view thereof;

FIG. 3 is a top view thereof;

FIG. 4 is an enlarged right side view of a portion defined by lines 4-4 in FIG. 2; and,

FIG. 5 is an enlarged right side view of a portion defined by lines 4-4 in FIG. 2 with all of the environmental subject matter being removed for clarity purposes.

In the drawings, the darkened out portions depict environmental subject matter only and form no part of the claimed design.

1 Claim, 5 Drawing Sheets

FIG. 1

FIG. 2**FIG. 3**

FIG. 4

FIG. 5
